J. T. L. Wright

WITNESS:

ATTORNEY

UNITED STATES PATENT OFFICE.

RYUJI SATO, OF NEW YORK, N. Y.

AMUSEMENT DEVICE.

Application filed September 13, 1923. Serial No. 662,502.

To all whom it may concern:

Be it known that I, RYUJI SATO, a citizen of Japan, residing at New York, in the county of New York and State of New York, have invented new and useful Improvements in Amusement Devices, of which the following is a specification.

This invention relates to amusement devices or game apparatus designed for use in amusement parks and like places.

The invention embodies amongst other features, an inclosure in which is arranged a basket like receptacle, the object of each participant being to kick as many of a predetermined number of balls allotted for each play into the basket, the balls being kicked singly and each having a scoring value, premiums being given to those who successfully obtain a certain high score or better.

In carrying out the invention, I provide a novel scoring device automatically actuated by a movable bottom of the basket like receptacle above referred to, each ball entering the basket passing through the latter and operating the bottom for the purpose specified.

Another object of the invention resides in the novel construction of a coin controlled mechanism operated to release the balls from a runway for play, the balls being singly released for this purpose.

Other objects and advantages of the invention will appear when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a longitudinal sectional view through the amusement device or game apparatus.

Figure 2 is a sectional view taken on the line 2—2 of Figure 1, looking in the direction of the arrows.

Figure 3 is a fragmentary sectional view showing the operation of the scoring device.

Figure 4 is a sectional view taken on the line 4—4 of Figure 3.

Figure 5 is a sectional view taken on the line 5—5 of Figure 2.

Figure 6 is a sectional view taken on the line 6—6 of Figure 2.

Figure 7 is a detail view of the coin actuated pawl and its cooperating part.

Figure 8 is a view similar to Figure 7 showing the initial position of the pawl when actuated by the coin.

Figure 9 is a detail view of the collar which cooperates with the pawl.

Figure 10 is a detail view of the shaft on which the collar is mounted.

The amusement device is in the nature of a game apparatus, and embodies an inclosure of elongated contour, and this inclosure can be constructed of any suitable material and vary in size without departing from the spirit of the invention. As shown in this specific instance, the inclosure preferably consists of a frame 10 including a bottom 11, the frame being covered by wire screening or the like 12. The frame is closed at one end, but open at the opposite end where the player stands in order to play the game. Arranged within the inclosure is a runway 13 to accommodate a predetermined number of balls 14, the balls being normally confined within this runway by means of a pivoted door 15. Extending diagonally across the bottom 11 from the innermost end of the runway 13 is a partition 16 which directs the balls into the runway after the same are played. The balls 14 may be of any suitable construction for the purpose intended, it being understood that it is the object of each player of the game to stand at the open end of the inclosure and kick the balls singly into the basket like receptacle 17 supported at the opposite end of the inclosure. In Figure 1, I have illustrated a figure 18 representing a player in the act of kicking one of the balls just described. Each ball has a fixed scoring value, and the game is successfully played when the participant kicks a certain number of the balls into the basket, netting a high score, for which a premium or the like is awarded. The receptacle 17 can of course be of any suitable size and construction, but includes a bottom 19 pivoted as at 20, the bottom being in a closed position as shown in Figure 1, and automatically swung into an open position as shown in Figure 3 by the weight of the ball passing therethrough. This bottom 19 is equipped with

an operating arm 21 which controls the operation of a scoring device supported upon the inclosure in full view of the participant, the scores being registered as the ball passes 5 through the receptacle 17.

This scoring device preferably embodies a casing 22 having a sight opening in the front wall thereof, which opening is normally closed by a transparent panel 23 19 through which the scores can be readily seen by the participant. Arranged within the casing 22 is a bladed wheel 24, the blades 25 radiating from the wheel and equi-distantly spaced apart. One side of 15 each blade is provided with a certain score, the scores being uniformly increased in consecutive order of the blades. For instance, the first blade in order is provided with a zero, the next blade is provided with —10—, 20 the next blade —20—, and so on, it of course being manifest that there is one blade for each of the balls 14 used in playing the game. It might also be here stated, that any number of balls can be used with the 25 apparatus, however, eight or ten balls preferably constitutes a set. The wheel 25 is fixed upon a shaft 26, and this shaft is journalled in any suitable manner within the casing 22. Associated with this shaft is a 30 ratchet wheel 27, with which a spring pressed pivoted pawl 28 cooperates in order to turn the shaft and the bladed wheel step by step to score the game. This pawl 28 is carried by an offset extremity 29 of a reciprocating rod 30, the latter being vertically disposed at one end of the inclosure and operable through suitable guides 31. The operating arm 21 above referred to is carried by the pivoted bottom 19 of the receptacle and is bifurcated to straddle the 40 rod 30, and this arm operates between spaced collars 32 and 33 respectively carried by the rod 30. A coil spring 34 encircles the rod 30 and has one end bearing against the collar 32 and its opposite end against 45 the free extremity of the arm 21 holding the latter against the collar 33, and also maintaining the pivoted bottom 19 normally in its closed position. As each ball enters 50 the receptacle 17 it drops upon the bottom 19, and automatically moves the bottom to an open position as shown in Figure 3. During this movement of the bottom, the arm 21 is moved upwardly compressing the 55 spring 34 which provides a connection between the arm 21 and the collar 32, so that the rod 30 is moved upwardly to the position shown in Figure 3, by dotted lines. It is during this upward movement of the rod 60 30 that the ratchet wheel 27 and the bladed wheel 25 is rotated one step or degree, bringing one of the blades 25 to view through the sight opening 23. As the ball passes from the receptacle 17, the spring 34 65 functions to return the rod 30 to its lower

position and automatically closes the bottom 19 of the receptacle. Those balls that drop from the receptacle 17 as well as the balls which fail to enter the receptacle, drop within the inclosure behind the partition 16, 70 and are directed to the runway 13, one behind the other as shown in Figure 1. After the game has been played, the scoring device can be conveniently returned to its normal position by reversing the rotation of 75 the bladed wheel 24. It might here be stated, however that when the wheel is rotated by means of the mechanism just described it is held against retrograde movement by means of a leaf spring 35 arranged 80 to bear against the hub of the wheel. For the purpose of returning the scoring device to normal position at the completion of the game, I preferably make use of a drum 36 which is fixed upon the shaft 26 of the scoring device. A flexible cable 37 has one end secured to this drum, and its opposite end secured to a somewhat similar drum 38 mounted upon a casing 39 which has a coin controlled mechanism for releasing the balls 85 from the runway and which is to be hereinafter described. However, this disposition of the drum 38 is within convenient reach of the participant, the drum being equipped with a handle 40 by means of 90 which the drum is rotated. The flexible cable 37 is trained through suitable guides 42 at the closed end of the inclosure, and passes underneath the apparatus through the guide 43 from where it is directed upwardly from where it is connected with the drum 38. When the game is being played, and the bladed wheel rotated for the purpose of scoring the game, the cable 37 is wound about the drum 36, and unwound 100 from the drum 38. However, at the completion of the game, it is only necessary to rotate the drum 38 by means of the handle 40 in a direction to wind the cable about said drum and incidentally unwind it from the 105 drum 36 which of course, reverses the rotation of the bladed wheel 24 and returns the wheel to its normal position. In playing the game, the participants stand on a pad or rubber platform 44 which is cut 110 away at one corner as shown in Figure 2, so that each ball played can be readily removed from the pocket or depression 45 at one side of the runway 13, the balls being singly dealt from the runway into the 115 pocket or depression, until all of the balls have been played. In passing of the balls from the runway 14 to the pocket 45 is as above stated controlled by the pivoted door 15, the latter being associated with a short 120 lever 46 pivoted as at 47. This lever is connected to the manually operable lever 48 by means of a link 49, the normal position of the lever being shown by full lines in Figure 6, and its active position shown by dot 125 130

ted lines in the same figure. When the lever is in its normal position, the door 15 is closed, and when the lever is moved rearwardly toward the participant, the door 5 is swung upwardly to allow one of the balls to pass through the runway 13 into the pocket or depression 45. The door can be repeatedly operated in this manner until the predetermined number of balls used in 10 playing the game have passed through the runway or depression, after which the door is locked in its closed position and cannot be released for further movement by the lever 48, until a coin of the proper denomination 15 has been inserted into the coin slot 50 of the casing 34. Arranged within this casing is a coiled spring 51, one end of which is connected to the casing 30 and its other end connected with the adjacent end 20 of the lever 48, the spring operating to normally hold the lever in the position shown by full lines in Figure 6 and the door 15 closed. Journalled within the casing 39 is a shaft 53 upon which is pivoted the manually operable lever 48. This shaft is rotated step by step, each operation of the lever 48 is through the instrumentality of a ball and ratchet connection as illustrated. The ratchet wheel 54 is fixed upon the shaft 30 53, while the pawl 55 is carried by the lever 48, and each time the lever is moved rearwardly to open the door, the shaft 53 is rotated a predetermined distance. In other words, the ratchet wheel 54 makes one complete revolution to effect the release of all 35 of the balls from the runway 13, the ratchet wheel having one tooth for each ball as will be readily understood. Loosely mounted upon the shaft 53 and at one side of the ratchet wheel 54 is a collar 56 clearly shown in Figure 9, and notched as at 57 to receive the offset extremity 58 of the pivoted pawl 59. This pawl is pivoted at a point between its ends on a suitable bracket arranged 40 within the casing 34, the opposite end of the pawl being reversely offset and provided with a coin receiving recess 60 which normally coincides with the coin slot 61 of the casing 39. The pawl normally maintains 45 the collar 56 fixed with relation to the shaft 53, so that the mechanism cannot be operated to open the door 15 until the pawl 59 is actuated to release the collar 56. This is accomplished by inserting within the coin slot 61 a coin of proper denomination, which coin passes through the slot into the recess 60 of the pawl. The weight of the coin overbalancing the pawl 59, thus moving the latter out of the notch 57 of the 50 collar 56. This collar is peculiarly constructed, so that just as soon as the pawl 59 is actuated under the influence of the coin just referred to, the collar will be initially rotated a predetermined distance to 1 move 65 the notch 57 thereof out of alignment with

the operating extremity of the pawl 59, so that the latter cannot be again received by the notch 57 upon its return to normal position. Manifestly the coin drops from the pawl 59 into the casing 39 when the pawl is 70 swung upon its pivot, this operation is clearly shown by dotted lines in Figure 8, just as soon as the coin separates itself from the pawl, the latter gravitates to its normal position but not into the notch 57 of the collar 56. In order to obtain this initial movement of the collar 56 for the purpose above stated, I provide the collar at one end with a hollow boss 62 of arcuate shape formation, the boss being closed at one end and 80 open at its opposite end as clearly shown in Figures 7 and 8. This boss operates between angularly disposed lugs 63 and 64 which project from the shaft 53. Arranged within this hollow boss 62 is a coiled spring 65, one end of which bears against the closed end of the boss, while the opposite end of the spring bears against the lug 64. The normal position of these parts with relation to the pawl 59 is shown in Figure 7, and just 85 as soon as the pawl is actuated under the weight of the coin, it assumes the position shown by dotted lines in Figure 8, at which time the spring 65 expands slightly turning the collar 56 upon the shaft 53 to move the 90 notch 57 to a position where it cannot again receive the working end of the pawl until the collar 56 has made one complete revolution. This initial adjustment of the collar 56 is shown in Figure 8, wherein it will be 95 noted that the closed end of the hollow boss is now in contacting engagement with the lug 63 of the shaft 53. With the parts in this position, the lever 48 can be actuated in the manner above described each time a 100 ball is needed from the runway 13, and when the distinct number of balls to which the player is entitled to has been released from the runway, the collar 56 will have made one complete revolution bringing the 105 notch 57 back to its normal position where it can again receive the working end of the pawl 59, this of course locking the mechanism against further operation until another coin is inserted within the coin slot 61. 110

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I 125 claim:

1. In a game apparatus, an inclosure, a receptacle arranged therein and including a pivoted bottom, a plurality of balls adapted to be singly kicked in the direction of the receptacle in an effort to deposit said balls 130

4
therein, each ball opening the pivoted bottom of the receptacle as it passes through the latter, a scoring device, means automatically operable to actuate the scoring device with each opening of the bottom of said receptacle, and a runway arranged upon the bottom of the inclosure to receive said balls.

2. In a game apparatus, coin controlled mechanism therefor including a casing, a normally closed door, a shaft mounted within the casing for rotation, a manually operable lever pivoted on the shaft and connected with said door and adapted to open the latter upon movement of the lever in one direction, a ratchet wheel fixed to said shaft, a

pawl carried by the lever and engaging said wheel to rotate said shaft intermittently, a collar loosely mounted on the shaft for initial rotation independently thereof, said wheel having a notch, and a coin actuated pawl pivoted within the casing and normally received by said notch to prevent rotation of the shaft and movement of said lever, and means for initially rotating said collar incident to the initial movement of said pawl, whereby the notch is moved out of alignment with the latter for the purpose specified. 20 25

In testimony whereof I affix my signature.
RYUJI SATO.
